UNITED STATES PATENT OFFICE.

PHILIP C. ANDERSON, OF LINCOLN, NEBRASKA, ASSIGNOR, BY MESNE ASSIGNMENTS, TO WESTERN WHEELED SCRAPER COMPANY, OF AURORA, ILLINOIS, A CORPORATION OF ILLINOIS.

WHEELED SCRAPER.

Application filed April 13, 1925, Serial No. 22,828. Renewed August 7, 1926.

My invention relates to improvements in wheeled scrapers, more particularly to scrapers for use on road construction or the like, and it consists in the combinations, constructions, and arrangements herein described and claimed.

An object of my invention is to provide a scraper of a substantially cylindrical form which is mounted on wheels, and which is primarily designed to be drawn by horses, novel means being provided whereby the scraper may be emptied of its contents in a continuous movement forward, thus obviating the necessity of stopping the device, backing it up, and manually righting it, as is necessary with ordinary scrapers.

A further object of my invention is to provide a wheeled scraper, wherein the bucket is pivotally mounted in such a manner that the operator may rock the bucket from loading position into carrying position without the necessity of manually lifting the load as is the case with standard bucket scrapers.

A further object of my invention is to provide a wheeled scraper of compact form, wherein the supporting wheels are disposed within the cutting edge of the scraper.

A further object of my invention is to provide a wheeled scraper which can not only carry a much larger load than can be carried by ordinary scrapers, but can be operated readily by one person, while the ordinary devices require two or more operators.

Other objects and advantages will appear in the following specification, and the novel features of the invention will be particularly pointed out in the appended claims.

My invention is illustrated in the accompanying drawing, forming part of this application, in which—

Figure 1 is a side elevation of the device,

Figure 2 is a plan view of the device,

Figure 3 is a section along the line 3—3 of

Figure 2,

Figure 4 is a section along the line 4—4 of

Figure 1, and

Figure 5 is a section along the line 5—5 of

Figure 3.

In carrying out my invention, I provide a frame 1, preferably made of a channel iron of the shape shown in Figures 1 and 2. A pair

I will now describe the bucket, see Figure 1. The bucket 3 is formed of two sides 4, substantially circular in shape, but having flattened portions for a purpose hereinafter described. The sides 4 are reenforced by angle irons 5, which are composed of sides 6 and 7. The portions 6 are riveted to the sides 4 in such a manner that the outer surface of the portions 7 will follow the contour of the sides 4. A sheet metal plate 8 conforms to the contour of the sides 4, between the points 9 and 10, and it is riveted to the portions 7 of the angle irons 5. This plate 8 forms the bottom 11 and the back 12 of the bucket. The back 12 has integral flanges 13 projecting at right angles from the sides of the bucket. The foremost portions of the sides 4 are turned outwardly at 14 and are rigidly secured to the forward ends of a pair of plates 15, the rearward ends of the plates being rigidly secured to the flanges 13.

A pair of wheels 16 is disposed, one on each side of the bucket 3, in a manner hereinafter described. The sides 4 and plates 15 are provided with openings 17 and 18 respectively. External bearings 19, having annular flanges 20, are placed against the outside of the plates 15, the flanges 20 projecting through the openings 18, and being rigidly held in place by bolts 21. The external bearings 19 are rotatably disposed within the bearings 2. Each of the external bearings 19 is provided with a bore 22 and a partition 23. The partition 23 has two threaded openings 24 and 25. An oil cup 24' is screwed into each of the openings 24.

The wheels 16 are placed in the spaces between the sides 4 and plates 15, the hubs 26 of the wheels being in alignment with the openings 17 and 18. Hollow axles 27 are passed through the hubs 26 and into the bores 22 until they strike against the partition 23. Rods 28, threaded at both ends, are passed through the hollow axles 27 and their outer ends are screwed into the openings 25.

Internal bearings 29, each having an annular flange 30, and a threaded opening 31 in the central portion thereof, are placed over the inner ends of the axles 27 until the threaded openings 31 are in position to receive the inner ends of the rods 28. The bearings 29

ing the bearings 29 to the sides 4 the mounting of the wheels and bucket is completed.

A U-shaped apron 32 is located in advance of the bucket, and is provided with upright portions 33 which are pivotally secured to the opposite sides of the frame 1 forward of the wheel axes, by pivots 34, as shown in Fig. 1. Said apron is adapted to swing fore and aft about said pivots into or out of operative relation to the front margins of the bucket, as will be evident from a comparison of Figs. 1 and 3. The arrangement is such that when the parts are in loading, or in carrying position, the rear margin of the apron underlies the front margin of the bucket and supports it against independent rocking in a clockwise direction as viewed in Fig. 1, and, therefore, serves as a means for controlling its position. The apron may, however, be swung forward away from the bucket, as shown in Fig. 3, to permit the load to be discharged, as will be hereinafter explained. In loading the apron serves also as a scraper to take up the dirt, and direct it to the bucket, as indicated by the dotted lines in Fig. 1, said apron being provided with a front cutting edge for that purpose. The apron 32 is moved into and out of engagement with the bucket by means about to be described. A rock shaft 34', having two levers 35 keyed thereto near its opposite ends, is rotatably mounted upon the frame 1. A pair of links 36, adjacent to the sides of the bucket, are provided with integral pins 37 which extend at right angles to the body of the links. The pins 37 are inserted in openings in the upturned portions 33, and the free ends of the links 36 are pivotally connected to the levers 35. A hand lever 38 is keyed onto one end of the shaft 34', and the operator, by moving the hand lever 38 up or down, can disengage the apron from the bucket, or lower the apron and the front of the bucket into scraping position.

The means for lowering the front of the bucket into loading position comprises bars 39 at opposite sides of the bucket, which are pivotally connected at one end to the levers 35 and their free ends formed into the shape of hooks 40. When the hand lever 38 is actuated in a manner so as to lower the apron, the swinging movement of the upper ends of the levers 35 will draw the bars 39 forwardly causing the hooks 40 to engage with lugs 41 which are upon the external bearings 19, and thus rotate the bucket to lower its front edge in cooperation with the apron.

The device is provided with a tongue 42 which is rigidly secured to the frame 1 and to a channel iron 43, the channel iron 43 extending across the tongue and being riveted to the sides of the frame. A bar 44, connected to the frame 1 by means of chains 45, and to the apron by means of links 46, is provided with a pair of sheaves 47. A chain or steel rope 48 is passed around the sheaves 47 in

a manner shown in Figure 2 and its ends secured to single-trees 49. Thus the draft is applied directly to the apron.

At the rear end of the frame 1 a board 50 is rigidly secured, thus providing a platform 70 upon which the operator may stand. A support 51, preferably U-shaped, is mounted upon the frame in front of the board 50. A hook 52 is mounted upon the support 51 at one side thereof, for the purpose of holding 75 the hand lever 38 against upward movement when the scraper is in normal or transport position.

From the foregoing description of the various parts of the device, the operation thereof may be readily understood. Figure 1 shows the carrying or transport position of the scraper. It is primarily designed to be drawn by horses, but may of course be drawn by a tractor, and it is lowered to scraping 85 or loading position, as indicated by dotted lines in Fig. 1, by first freeing the hand lever 38 from the hook 52, and raising said lever to the proper height. By raising the hand lever, the shaft 34' is rocked and the levers 35, together with the links 36, swing the apron 32 downwardly and rearwardly to loading position. As the levers 35 are actuated, the bars 39, which are pivotally secured thereto, engage with the lugs 41 at the 95 hooked portions 40, and in this manner the bucket 3 is rocked forward until it is held from further movement by the apron. The parts being in the loading position shown by dotted lines in Fig. 1, the apron scrapes up 100 the material to be loaded and delivers it to the bucket. The apparatus can be made to cut at any desired depth merely by raising the hand lever 38 to a predetermined height and holding it there until the bucket is filled. 105

The bucket being filled, the hand lever 38 is lowered and placed under hook 52. This brings the bucket and apron up into carrying position again, as shown in full lines in Fig. 1, and they are held in this position until 110 the scraper reaches the place where the contents thereof are to be emptied.

At this point, I wish to draw special attention to the diameter of the sides 4. It will be observed that the diameter of the sides 4 is 115 somewhat greater than that of the wheels 16, and that both sides 4 and wheels 16 are pivotally mounted at their centers upon the same axis.

To empty the bucket, the hand lever 38 is 120 pressed downwardly below the hook. This actuates the rock shaft 34' in a counterclockwise direction as seen in Fig. 3, and moves the levers 35, and links 36, in a manner so as to swing the apron 32 forward and upward 125 away from the bucket 3. This is usually done while the scraper is still in motion. When the apron 32 is free from the bucket, as shown in Fig. 3, levers 53, which are pivotally mounted upon the inner surface of the plates 130

15 and are provided with lugs 54, will drop so that the lugs 54 will engage with ratchets 55. The ratchets are integral with the wheels 16 and as the lugs 54 engage therewith, the 5 bucket is forced to rotate with respect to the wheels until it strikes the ground, as also shown in Fig. 3. At this point, the carriage or supporting structure starts to ride upon the bucket, with the wheels clear of the 10 ground, and as the scraper is drawn forward, because of its engagement with the ground, the bucket is revolved, further, until it makes a complete turn, thus emptying its contents. However, before the bucket makes a complete 15 revolution, the hand lever 38 is released and allowed to assume its normal position again in engagement with the hook 52. The purpose of this is to lower the apron 32 into its normal position. Therefore, when the bucket 20 has revolved far enough to empty its load, the wheels 16 will again engage with the ground and the apron 32 will catch the bucket and retain it in normal position.

Drawing attention again to the levers 53, 25 it will be observed that the forward free ends 56 thereof are bent outwardly at right angles to the length of the levers. When the apparatus is in normal position, the ends 56 rest upon the projections 57 of the bars 39, and 30 in this manner the lugs 54 are held out of engagement with the ratchets 55. When the hand lever 38 is forced downwardly, the projections 57 will slip out from under the ends 56 and allow the levers 53 to fall, thus permitting the lugs 54 to engage with the ratchets 55. This is the means for positively 35 starting the revolution of the bucket to empty the contents thereof. When the bucket completes its revolution, the projections 57 of the bars 39 which have regained their normal position, will catch the ends 56 and hold the levers 53 in a position so that the lugs 54 will 40 not engage with the ratchets 55. As the bucket turns over the free ends of the levers 45 53 are held against dropping down into engagement with the ground by stop lugs 58 extending inwardly from the upper edges of the side plates 15 in position to hold the levers 53 in proximity to the ratchet wheels 55.

50 It will be observed that the bucket has a load-receiving edge, which is adapted to be lowered with the apron, and to receive the material to be loaded as it is cut from the ground by the apron. When the bucket is 55 again brought back to normal or transport position, the apron swung free from the bucket, and the latter rotated, the load-receiving edge is the first portion of the bucket to come in contact with the ground. At this 60 point, as the forward movement continues, the wheels are swung free from the ground, and the bucket is rotated into dumping position.

I claim:

65 1. A scraper comprising a pair of wheels,

a substantially cylindrical bucket of greater diameter than the wheels and mounted coaxially therewith, said bucket having a load-receiving edge adapted to be brought into contact with the ground, whereby the bucket 70 is brought to dumping position, and an apron for delivering material to the bucket and arranged to be engaged by the bucket when the latter is moved from dumping position.

2. A device of the type described comprising a frame, a bucket, said bucket having substantially circular sides and a flat bottom, a pair of wheels slightly smaller in diameter than said sides, said wheels being rotatably mounted upon said bucket at the center of 75 said sides, said bucket being rotatably mounted upon the frame at the center of said sides, and a U-shaped apron pivotally mounted upon said frame and extending under the bottom of said bucket at the forward end thereof. 80

3. A device of the type described comprising a frame, a bucket, said bucket composed of a pair of substantially circular sides and an arcuate shaped back merging into a flat bottom, a pair of wheels slightly smaller in 90 diameter than said sides, said wheels being rotatably mounted upon said bucket at the center of said sides, said bucket rotatably mounted upon the frame at the center of said sides, a U-shaped apron pivotally mounted 95 upon said frame and extending under the bottom of said bucket at the forward end thereof, and manually controlled means for freeing the apron from said bucket.

4. A device of the type described comprising a frame, wheels supporting said frame, a bucket carried by said frame, an apron in advance of the bucket, pivotally connected with the frame and adapted to engage the front edge of the bucket to hold the same in carrying position, and means whereby the apron may be turned to load receiving position, said means comprising a rock shaft mounted upon said frame, a lever operable to rock said shaft, a lever rigidly mounted upon said shaft, and a link connecting the latter lever with said apron, whereby by rocking said rock shaft in one direction said apron may be moved to free the bucket. 100

5. A scraper comprising a frame, a bucket pivotally carried by said frame for rotative dumping movement, and means for holding said bucket in loading and in carrying position, said means also acting as a digging member for filling the bucket with dirt. 110

6. A scraper comprising a frame, a bucket tiltably carried by said frame for forward dumping movement, and a dirt digging member carried by said frame, said member also supporting said bucket in loading and in carrying position. 120

7. A scraper comprising a frame, a bucket pivotally carried by said frame for complete rotative movement, and an apron for supporting said bucket in loading and in carry- 125

- ing position, said apron also being adapted to dig into the ground and convey the dirt to the bucket.
8. A scraper comprising a frame, a bucket carried by said frame, and a scraping member for directing the material to be loaded into said bucket, said scraping member being movable into and out of operative engagement with the front edge of the bucket.
10. 9. A scraper comprising a frame, a bucket carried by said frame, and a scraping member for directing the material to be loaded into said bucket, said scraping member being pivotally mounted on the frame to swing fore and aft in advance of the bucket and being movable into and out of operative engagement with the front edge of the bucket.
10. A scraper comprising a frame, a bucket mounted on said frame to rock about a transverse axis, and a scraping member for directing the material to be loaded into the bucket pivotally mounted on said frame to swing toward and from the front edge of the bucket.
11. A scraper comprising a frame, a bucket carried by said frame, a scraping member for directing the material to be loaded into said bucket, said scraping member being movable into and out of operative engagement with the front edge of the bucket, and draft means connected with said scraping member.
12. A scraper comprising a frame, a bucket pivotally carried by said frame to rock about a transverse axis, a scraping member for directing the material to be loaded into said bucket, said scraping member being pivotally mounted on the frame to swing fore and aft in advance of the bucket and being movable into and out of operative relation to the front edge of the bucket, and draft means connected with said scraping member.
13. A scraper comprising a frame, a bucket mounted on said frame to rock about a transverse axis for rotative dumping movement, a scraping member for directing the material to be loaded into the bucket pivotally mounted to swing toward and from the front edge of the bucket, and draft means connected with said scraping member.
14. A scraper comprising a frame, a bucket pivotally carried by said frame for rotative dumping movement, means for holding said bucket in loading and in carrying position, said means also acting as a digging member for filling the bucket with dirt, and draft means connected with said digging member.
15. A scraper comprising a frame, a bucket pivotally carried by said frame for rotative dumping movement, a dirt digging member carried by said frame, said member also supporting said bucket in loading and in carrying position, and draft means connected with said digging member.
16. A scraper comprising a frame, a bucket pivotally carried by said frame for complete rotative movement, an apron for supporting said bucket in loading and in carrying position, said apron also being adapted to dig into the ground and convey the dirt to the bucket, and draft means connected with said apron.
17. A scraper comprising a frame, a bucket supported by said frame to rock about a transverse axis, scraping means pivotally connected with said frame eccentrically to the axis of said bucket for directing material into said bucket, said bucket being rockable on its axis independently of said scraping means, said scraping means being movable into and out of position to hold the bucket against rocking independently thereof.
18. A scraper comprising a frame, a bucket supported by said frame to rock about a transverse axis, scraping means pivotally connected with said frame eccentrically to the axis of said bucket for directing material into said bucket, said bucket being rockable on its axis independently of said scraping means, said scraping means being movable into and out of position to hold the bucket against rocking independently thereof, and draft means connected with said scraping means.
19. A scraper comprising a frame, a bucket supported on said frame for rotative movement through a complete revolution, and means actuated by forward movement of the scraper for rocking the bucket to tip its front edge into engagement with the ground.
20. A scraper comprising a frame, a bucket supported thereby to rock about a transverse axis, means actuated by forward movement of the scraper for rocking the bucket to tip its front edge into engagement with the ground, and scraping means for directing material into said bucket, said scraping means being movable into and out of operative relation to the bucket.
21. A scraper comprising a frame, a bucket supported thereby to rock about a transverse axis, means actuated by forward movement of the scraper for rocking the bucket to tip its front edge into engagement with the ground, and scraping means for directing material into said bucket, said scraping means being movable into and out of operative relation to the bucket and serving to hold the bucket against rocking independently thereof when the scraper is in loading position.
22. A scraper comprising a frame, a bucket supported thereby to rock about a transverse axis, means actuated by forward movement of the scraper for rocking the bucket to tip its front edge into engagement with the ground, scraping means for directing material into said bucket, said scraping means being movable into and out of operative relation to the bucket and serving to hold the bucket against rocking independently thereof.

- thereof when the scraper is in loading position, and means operable to move said scraping means out of engagement with the bucket to permit the latter to be dumped.
- 5 23. A scraper comprising a frame, a bucket supported thereby to rock about a transverse axis, means actuated by forward movement of the scraper for rocking the bucket to tip its front edge into engagement with the ground, scraping means for directing material into said bucket, said scraping means being movable into and out of operative relation to the bucket and serving to hold the bucket against rocking independently thereof when the scraper is in loading position, and draft means connected with said scraping means.
- 10 24. A scraper comprising a frame, a bucket supported thereby to rock about a transverse axis, means actuated by forward movement of the scraper for rocking the bucket to tip its front edge into engagement with the ground, scraping means for directing material into said bucket, said scraping means being movable into and out of operative relation to the bucket and serving to hold the bucket against rocking independently thereof when the scraper is in loading position, means operable to move said scraping means out of engagement with the bucket to permit the latter to be dumped, and draft means connected with said scraping means.
- 15 25. A scraper comprising a frame, a rotatable bucket pivotally supported by said frame to turn about a transverse axis for rotative dumping movement, and scraping means mounted to swing fore and aft in front of the bucket, and movable into engagement therewith to form an extension thereof.
- 20 26. A scraper comprising a frame, a rotatable bucket pivotally supported by said frame to turn about a transverse axis, and scraping means mounted to swing fore and aft in front of the bucket, and movable into and out of engagement therewith, said scraping means being adapted to form an extension of the bucket, and also being arranged to support the front edge of the bucket when the scraper is in loading position.
- 25 27. A scraper comprising a frame, a rotatable bucket pivotally supported by said frame to turn about a transverse axis, and scraping means mounted to swing fore and aft in front of the bucket, and movable into and out of engagement therewith, said scraping means being adapted to form an extension of the bucket, said scraping means also being arranged to support the front edge of the bucket when the scraper is in carrying position.
- 30 28. A scraper comprising a frame, a rotatable bucket pivotally supported by said frame to turn about a transverse axis, and scraping means mounted to swing fore and aft in front of the bucket, and movable into
- and out of engagement therewith, said scraping means being adapted to form an extension of the bucket, said scraping means also being arranged to support the front edge of the bucket when the scraper is in loading and in carrying position.
- 35 29. A scraper comprising a frame, a rotatable bucket pivotally supported by said frame to turn about a transverse axis, scraping means mounted to swing fore and aft in front of the bucket, and movable into engagement therewith to form an extension thereof, said scraping means being arranged to support the front edge of the bucket when the scraper is in carrying position, and means actuated by forward movement of the scraper for positively rotating the bucket to tip its front edge into engagement with the ground.
- 40 30. A scraper comprising a frame, a rotatable bucket pivotally supported by said frame to turn about a transverse axis, scraping means mounted to swing fore and aft in front of the bucket, and movable into engagement therewith to form an extension thereof, said scraping means being arranged to support the front edge of the bucket when the scraper is in loading and in carrying position, and means actuated by forward movement of the scraper for positively rotating the bucket to tip its front edge into engagement with the ground.
- 45 31. A scraper comprising a frame, a bucket supported by said frame to rotate about a transverse axis, a scraping member pivotally supported by the frame eccentrically to the axis of the bucket and movable into and out of position to form a forward extension of said bucket, said scraping member serving also to support the front edge of the bucket when it is in loading or in carrying position.
- 50 32. A scraper comprising a frame, a bucket supported by said frame to rotate about a transverse axis, a scraping member pivotally supported by the frame eccentrically to the axis of the bucket and movable into and out of position to form a forward extension of said bucket, said scraping member serving also to support the front edge of the bucket when it is in loading or in carrying position, and means operable to move said scraping member away from the bucket to permit the bucket to be dumped.
- 55 33. A scraper comprising a frame, a bucket supported by said frame to rotate about a transverse axis, said bucket having peripheral portions movable into engagement with the ground for effecting its rotation by the forward movement of the scraper, and a scraping member supported by the frame to swing toward and from the front edge of the bucket for directing the material to be loaded thereinto.
- 60 34. A scraper comprising a frame, a bucket supported by said frame to rotate about a transverse axis, said bucket having periph-

- eral portions movable into engagement with the ground for effecting its rotation by the forward movement of the scraper, and a scraping member supported by the frame to 65
 5 swing toward and from the front edge of the bucket for directing the material to be loaded thereinto, said scraping member serving also to support the front edge of the bucket when it is in loading or in carrying position.
10. 35. A scraper comprising a frame, a bucket supported by said frame to rotate about a transverse axis, said bucket having peripheral portions movable into engagement with the ground for effecting its rotation by the 70
 15 forward movement of the scraper, a scraping member supported by the frame to swing toward and from the front edge of the bucket for directing the material to be loaded thereinto, said scraping member serving also to 75
 20 support the front edge of the bucket when it is in loading or in carrying position, and draft means connected with said scraping member.
36. A scraper comprising a frame, a scraping member carried by said frame and movable into and out of scraping position, and a bucket for receiving scraped material from said scraping member, said bucket being completely rotatable, separately from said scraping member, to discharge its load. 80
- 30
37. A scraper comprising a frame, a scraping member carried by said frame and movable into and out of scraping position, a bucket for receiving scraped material from said scraping member, said bucket being completely rotatable, separately from said scraping member, to discharge its load, and draft means connected with said scraping member. 85
- 35
38. A scraper comprising a wheeled frame, a bucket mounted on said frame to turn about a transverse axis, the front portion of said bucket being wider than the tread of said wheels, and a scraping member supported by said frame to swing fore and aft in advance 90
 40 of the bucket and movable into operative relation therewith to form an extension thereof. 100
39. In a scraper, the combination with a wheel supported frame, of a scraper comprising a bucket mounted to rotate about a transverse axis and comprising side plates located outside of said wheels, and a scraping member mounted on said frame to swing toward and from the front edge of the bucket to form a forward extension thereof when the same is 105
 45 in loading or carrying position. 110
40. In a scraper, the combination with a wheel supported frame, of a scraper comprising a bucket mounted to rotate about a transverse axis and comprising side plates located outside of said wheels, a scraping member mounted on said frame to swing toward and from the front edge of the bucket to form a forward extension thereof when the same is 115
 50 in loading or in carrying position, draft 120
 55 means connected with said scraping member, and means operable to move said scraping member out of operative relation to the bucket. 125
41. In a two wheeled dumping scraper of the class described, the combination of a frame comprising side frame bars, a pair of axially aligned wheels disposed on the inner sides of said frame bars, a bucket disposed between said wheels, pivotal mountings connecting the bucket and wheels with said frame bars at each side of said frame comprising inner and outer spaced coaxial bearing members, said inner bearing members being secured to the side walls of said bucket, said outer bearing members being secured to said frame bars, hollow axles having their end portions extending into said bearing members, said wheels being mounted on said hollow axles, and threaded connecting members extending through said hollow axles and connecting said bearing members, said bucket being rotatable through a complete revolution on the axis of said wheels when dumping. 130
42. A scraper comprising a frame, a pair of axially aligned wheels supporting said frame, a bucket pivotally mounted on said frame for complete rotative movement about the axis of said wheels, and means actuated by forward movement of the scraper for rocking the bucket to tip its front edge into engagement with the ground. 135
43. In a two wheeled dumping scraper, the combination of a frame comprising side frame bars, a pair of axially aligned wheels disposed on the inner sides of said frame bars, a rotatable bucket disposed between said wheels, a stub axle at each side of said frame extending from said side frame bars inwardly through said wheels and having their inner ends engaging with the side walls of said bucket, and plate members secured to said bucket and engaging with said stub axles at points between said wheels and said side frame bars. 140
44. In a two wheeled dumping scraper, the combination of a frame comprising side frame bars, stationary bearing members secured to said frame bars, a pair of axially aligned wheels disposed on the inner sides of said frame bars, a bucket disposed between said wheels and adapted to have rocking movement about the axis thereof, plate members secured to and rocking with said bucket, said plate members being disposed on the outer sides of said wheels, rotatable bearings secured to said plate members and having bearing engagement in said stationary bearing members, and axles having their outer ends supported in said rotatable bearings and extending through said wheels and having their inner ends engaging with the side walls of said bucket. 145

PHILIP C. ANDERSON.
